VALVE HANDLE SECURING HASP

Michael R. Plympton, Houston, Tex., assignor to
ACF Industries, Incorporated, New York, N.Y.

Filed Aug. 4, 1975, Ser. No. 601,877

Term of patent 14 years

Int. Cl. D8—07

U.S. Cl. D8—137

FIG. 1

FIG. 3

FIG. 2

FIG. 4

FIG. 5

FIG. 6

FIG. 7

FIG. 8

FIG. 9

FIG. 10

FIG. 11

FIG. 12

FIG. 13

FIG. 1 is a perspective view of a valve handle securing hasp embodying my new design;

FIG. 2 is a top plan view thereof;

FIG. 3 is a bottom plan view thereof;

FIG. 4 is a side elevational view thereof;

FIG. 5 is an elevational view taken from the side opposite that shown in FIG. 4;

FIG. 6 is an end elevational view thereof;

FIG. 7 is an elevational view taken from the end opposite that shown in FIG. 6;

FIG. 8 is another perspective view thereof, showing the valve handle securing hasp in a second operating position;

FIG. 9 is a top plan view of FIG. 8;

FIG. 10 is a bottom plan view of FIG. 8;

FIG. 11 is a side elevational view of FIG. 8;

FIG. 12 is an elevational view taken from the side opposite that shown in FIG. 11;

FIG. 13 is an end elevational view of FIG. 8; and

FIG. 14 is an elevational view taken from the end opposite that shown in FIG. 13.

The broken line representation of the valve, valve handle, and padlock shown in FIGS. 1, 4, 5, 8, 11 and 12 is for purposes of illustration only.

I claim:

The ornamental design for a valve handle securing hasp, as shown and described.
